(57) **CLAIM**

The ornamental design for a securement device assembly, as shown and described.

DESCRIPTION

FIG. 1 is a top perspective view of a securement device assembly showing our new design in an assembled configuration, with tubing and support material shown as unclaimed environmental subject matter;

FIG. 2 is a top perspective view of the securement device assembly of FIG. 1;

FIG. 3 is a bottom perspective view of the securement device assembly of FIG. 1;

FIG. 4 is a top plan view of the securement device assembly of FIG. 1;

FIG. 5 is a right side elevation view of the securement device assembly of FIG. 1, the left side elevation view being a mirror image thereof;

FIG. 6 is a front elevation view of the securement device assembly of FIG. 1;

FIG. 7 is a rear elevation view of the securement device assembly of FIG. 1;

FIG. 8 is a bottom plan view of the securement device assembly of FIG. 1;

FIG. 9 is a perspective view of the securement device assembly of FIG. 1 in a disassembled configuration;

FIG. 10 is a top perspective view of a first component of the securement device assembly of FIG. 1;

FIG. 11 is a bottom perspective view of the first component shown separately for ease of illustration;

FIG. 12 is a top plan view of the first component;

FIG. 13 is a right side elevation view of the first component, the left side elevation view being identical thereto;

FIG. 14 is a front elevation view of the first component, the rear elevation view being identical thereto;

FIG. 15 is a bottom plan view of the first component;

FIG. 16 is a top perspective view of a second component of the securement device assembly of FIG. 1 shown separately for ease of illustration;

FIG. 17 is a bottom perspective view of the second component;

FIG. 18 is a top plan view of the second component;

(Continued)

FIG. 19 is a right side elevation view of the second component, the left side elevation view being a mirror image thereof;
 FIG. 20 is a front elevation view of the second component;
 FIG. 21 is a rear elevation view of the second component;
 FIG. 22 is a bottom plan view of the second component;
 FIG. 23 is a top perspective view of a third component of the securement device assembly of FIG. 1 shown separately for ease of illustration;
 FIG. 24 is a bottom perspective view of the third component;
 FIG. 25 is a top plan view of the third component;
 FIG. 26 is a right side elevation view of the third component, the left side elevation view being identical thereto;
 FIG. 27 is a front elevation view of the third component, the rear elevation view being identical thereto;
 FIG. 28 is a bottom plan view of the third component;
 FIG. 29 is a top perspective view of a fourth component of the securement device assembly of FIG. 1 shown separately for ease of illustration;
 FIG. 30 is a top plan view of the fourth component;
 FIG. 31 is a right side elevation view of the fourth component, the left side elevation view being identical thereto;
 FIG. 32 is a front elevation view of the fourth component, the rear elevation view being identical thereto; and,
 FIG. 33 is a bottom plan view of the fourth component.
 The broken lines depict unclaimed environmental subject matter and form no part of the claimed design.
